UNITED STATES PATENT OFFICE

JOHN J. COMPO, OF DEFIANCE, OHIO

THERMOSTATIC SWITCH

Application filed February 9, 1927. Serial No. 166,901.

The present invention relates to a thermostatic switch and has for its principal object to provide a structure which will make and break with a snap.

Another important object of the invention lies in the provision of a substantially U-shaped spring metal member carrying between its ends a thermostatic metal member which at normal temperature is bowed outwardly therefrom and in engagement with a contact but as the temperature rises, the thermostatic strip will expand to flex the ends of the U-shaped members so that when a predetermined point of expansion has been reached the thermostatic metal strip will bow inwardly with a snap to break the circuit.

A still further important object of the invention lies in the provision of a thermostatic switch of this nature which possesses an exceedingly simple construction that may be manufactured at a low cost and yet be thoroughly strong and durable in construction and exceedingly efficient and reliable in operation.

With the above and numerous other objects in view as will appear as the description proceeds, the invention resides in certain novel features of construction, and in the combination and arrangement of parts as will be hereinafter more fully described and claimed.

In the drawing:—

Figure 1 is a side elevation of the switch embodying the features of this invention showing the contacts engaged,

Figure 2 is a top plan view thereof,

Figure 3 is another side elevation thereof showing the points of contact separated,

Figure 4 is an end elevation thereof.

Referring to the drawing in detail, it will be seen that the numeral 5 denotes a spring metal base of U-shaped formation, one end of which is mounted on an insulator 6 by means of screws 7 or in any other suitable manner. The numeral 8 denotes a strip of thermostatic metal bound between the two upright ends of the U-shaped base 5 by having the ends of the strip 8 formed with notches 9 the side walls of which have recesses 10 to receive the edges of the upright sides of the U-shaped base. When the switch

is exposed to a desired temperature, the thermostatic metal strip will expand and force the upright ends of base 5 to spring apart enough to allow the thermostatic switch to snap downwardly past the center, breaking or separating contact points 11 and 12, the latter of which is fixed to the strip 8 thereby opening or disconnecting an electric circuit associated therewith. The upper contact 11 is in the form of a screw threaded through a substantially Z-shaped bracket 14 one end of which is fixed to an insulator 15 by means of screws 16 or in any other suitable manner. The contact 14 is held in the desired adjusted position by means of a lock nut 17. It is to be noted that the base 5 is mounted on the insulator 6 by the screw 7 so that both ends are free to move up or down to obtain the desired spring action. The hinge-like mounting provided by notches 9 with their recesses 10 will allow the thermostatic strip freedom to travel up or down for binding or clamping. Thus the action of the switch causes the points to break or open and also to close with a snap.

It is thought that the construction, operation, and advantages of this invention will now be apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as herein-after claimed or sacrificing any of its advantages.

Having thus described my invention, what I claim as new is:—

1. In a thermostatic switch of the class described, an insulator, a U-shaped base of spring material, means for attaching one end of the bight of the U-shaped base to the insulator, a stationary contact arranged above the base the ends of the base projecting upwardly from said bight, a thermostatic strip having notches formed in its ends with recesses in

the side walls thereof to receive the ends of the base to be bound there-between, said strip, being interposed between said base and the contact so that normally the strip at a predetermined temperature bows outwardly from the bight of the base and in engagement with said contact.

2. In a thermostatic switch of the class described, an insulator, a U-shaped base of 10 spring material, means for attaching one end of the bight of the U-shaped base to the insulator; a stationary contact the ends of the base projecting upwardly from said bight, a thermostatic strip having notches formed in 15 its ends with recesses in the side walls thereof to receive the ends of the base to be bound there-between so that normally the strip at a predetermined temperature bows outwardly from the bight of the base, a second insulator 20 for supporting the contact, and a Z-shaped bracket on the second insulator.

In testimony whereof I affix my signature.

JOHN J. COMPO.
